UNITED STATES PATENT OFFICE.

PETER WIGGEN, OF CHICAGO, ILLINOIS, ASSIGNEE TO J. P. SEEBURG PIANO COMPANY,
OF CHICAGO, ILLINOIS, A CORPORATION OF ILLINOIS.

MAGAZINE-SLOT FOR COIN-OPERATED MUSICAL INSTRUMENTS.

1,014,107.

Specification of Letters Patent.

Patented Jan. 9, 1912.

Application filed February 21, 1910. Serial No. 545,141.

To all whom it may concern:

Be it known that I, PETER WIGGEN, a citizen of the United States, residing at Chicago, in the county of Cook and State of Illinois have invented certain new and useful Improvements in Magazine-Slots for Coin-Operated Musical Instruments, of which the following is a specification.

This invention relates to improvements in a mechanism to be used in connection with that class of musical instruments in which the pneumatics thereof are operated by means of electricity for making and breaking contacts or for starting and stopping the motor which operates the instrument, and it consists in certain peculiarities of the construction, novel arrangement, and operation of the various parts thereof, as will be hereinafter more fully set forth and specifically claimed.

The principal object of the invention is to provide a mechanism of the above-named character to be operated by the deposit of one or more coins and is especially intended to receive several coins one at a time so that a number of tunes or pieces of music may be played by the instrument one after the other without the necessity of depositing a coin at the end of each piece or tune.

Other objects and advantages of the invention will be disclosed in the subjoined description and explanation.

In order to enable others skilled in the art to which my invention pertains, to make and use the same, I will now proceed to describe it, referring to the accompanying drawing, in which—

Figure 1, is a view partly in section and partly in elevation of a magazine slot mechanism embodying the invention, showing the parts in their initial positions or out of contact as they will appear when the musical instrument is at rest, or not in operation; Fig. 2, is a similar view of like parts, but showing them in contact or in position for playing a number of tunes or pieces; and Fig. 3, is a fragmental perspective view of a portion of the ratchet-toothed rack and a portion of the contact plate which it carries.

Like numerals of reference, refer to corresponding parts throughout the different views of the drawing.

The reference numeral 5, designates the main or supporting-frame of the mechanism, which may be made of any suitable

size, form and material, and adapted to be secured in the musical instrument at any suitable point. The frame is provided in one of its sides with a coin-chute 6, for conducting the deposited coins to a suitable receptacle therefor, not shown. The upper portion of the casing or frame 5, is provided with a slot 7, which may have communication with a coin-conducting-chute (not shown) leading from a suitable point in the casing of the instrument, for admitting coins to the chute 6, for actuating the operating-lever. The rear portion of the casing or frame 5, is provided near one of its sides with a vertical groove 8, or guide way for the rack 9, which has on each of its sides a series of ratchet-teeth 10, and 11, for engagement with spring-actuated pawls used for raising and lowering said rack. The rack 9, is made of fiber or other suitable insulating material, and has on its rear portion a vertical cleat 12, to fit in the guide way 8, and on its front surface a metal-plate 13, which is extended to near the ends of the rack. Fulcrumed at one of its ends on the frame 5, is an operating lever 14, which is extended through an opening 15, in the upper portion of a partition 16, which divides the coin chute 6, from the main portion of the casing or frame.

As is clearly shown in Figs. 1, and 2, of the drawing, the operating lever 14, is extended at its free end just below the slot 7, and is located in front of the rack 9, or on the opposite face thereof from the cleat or projection 12, of said rack, thus assisting in holding the rack in position. Extended inwardly from the back of the casing or frame 5, are two stop pins or projections 17, and 18, located above and below the operating lever 14, and used for limiting its upward and downward movements. Pivotedly secured at one of its ends to the operating lever 14, near the rack 9, is a depending pawl 19, adapted to engage the ratchet-teeth 11, on one side of the rack. This pawl is actuated by a spring 20, which has one of its ends secured to the upper portion of the pawl and its other end to a screw or projection 21, on the operating lever. Located in the lower portion of the casing 5, is a pneumatic of the ordinary or any well known construction which has on its lower portion at its free end an extension or arm 22, to which is pivotally secured near its free end the lower end of a

pawl 23, which has its upper portion provided with two bends 24, and 25, to coact with a pin 26, secured to the back of the casing or frame in such a manner as to hold the upper end of said pawl out of engagement with the ratchet-teeth 10, of the rack when the pneumatic 27, is inflated but to permit it to engage said teeth when said pneumatic is deflated. The pawl 23, is 10 pressed toward the rack 9, by means of a spring 28, which is secured at one of its ends to the pawl and at its other end to the extension 22, which extension also has pivotally secured thereto the lower end of a rod 29, which is pivoted at its upper end to one end of a link 30, the other end of which is pivotally secured on the back of the frame or casing and in such a manner that said link shall extend across the rack. The upper portion of the pneumatic has leading therefrom a tube 31, which communicates with a primary or power pneumatic (not shown) of the musical instrument. Secured to the back of the casing or frame and insulated therefrom by means of blocks 32, of suitable insulating material, are a pair of contact springs 33, and 34, each of which has its free end extended into the path of the metal plate 13, which is carried by the rack, against which plate and rack the springs 33 and 34, will contact so as to frictionally hold the rack in position on the frame. Connected to the contact springs 33, and 34, by means of binding posts 35, are electric conductors 36, and 37, which lead to the motor (not shown) used for operating the pneumatics of the instrument. The operating lever 14, is normally held with its free end in an elevated position as shown by continuous lines 40 by means of a spring 38, which has one of its ends applied to one side of the frame 5, and is passed over the fulcrum 39, and has its other end in engagement with the said lever.

45 From the foregoing and by reference to the drawing, it will be seen and understood that when the parts are in the positions shown in Fig. 1, the contact spring 34, will be out of contact with the metal plate 13, and that the pneumatic 27, will be inflated and the extension 22, thereon, held in its lowered position by means of the spring 40, which is connected at one of its ends to the partition 16, and at its other end to the lower 55 portion of the pneumatic. When the parts are in the aforesaid positions, it will be understood that by depositing a coin through the slot 7, the operating lever 14, will be depressed by the weight of the coin to the position shown by dotted lines in Fig. 1, in which operation the rack 9, will be moved downwardly the distance of one of its teeth, thus bringing the contact spring 34, into engagement with the plate 13, and thereby 60 completing the electric circuit through the

conductors 36, and 37, with the motor and causing the operation of the same, and through it the operation of the musical instrument. After the piece of music has been played, the pneumatic 27, will be deflated through the instrumentality of the tube 31, which as before stated, communicates with the power pneumatic of the instrument, in which operation it is evident that the extension 22, will be raised from the position shown in Fig. 1, in which movement the bend 25, of the pawl 23, will pass over the pin 26, and allow said pawl to engage one of the teeth 10, of the rack, and raise the same the distance of the length of one of said teeth, thus removing the plate 13, from out of contact with the spring 34, and causing the motor to cease its operation. It is apparent that if it is desired to cause the instrument to play several tunes or pieces one after the other, several coins may be deposited through the slot 7, one at a time, which will cause the rack 9, to be moved downwardly the distance of the length of one of the teeth 11, for each coin deposited, and that as the pneumatic 27, will be deflated at the end or finish of each piece of music, the rack will be elevated the distance of the length of one tooth 10, for each piece of music played, until the last one has been finished, when the metal plate 13, will be thrown out of contact with the contact spring 34, as above described. In the upward movement of the extension 22, on the pneumatic 27, the pawl 19, will be thrown out of engagement with the teeth 11, of the rack by means of the pivot pin 41, which connects the rod 29, to the link 30, and which pin is extended through said link toward the rack for the purpose of engaging said pawl.

Having thus fully described my invention what I claim as new and desire to secure by Letters-Patent is—

1. In a device of the character described, the combination with a supporting-frame, of a contact member movably mounted thereon, electrically connected contact springs extended into the path of said member, means adapted for engagement with and to move said member in one direction, and pneumatically operated means to move said member in the opposite direction and to disengage the first named means therefrom.

2. In a device of the character described, the combination with a supporting-frame, of a suitably fulcrumed lever, a movably mounted rack carrying a metal piece, a pawl pivotally secured to the lever and adapted to engage teeth on the rack, to move it in one direction, a pneumatic mounted on the supporting frame, a pawl carried by the pneumatic and adapted to engage teeth of the rack to move it in the opposite direction, and electrically connected contact springs mounted on the supporting-frame and ex-

tended into the path of the metal piece on the rack.

3. In a device of the character described, the combination with a supporting-frame, 5 of a suitably fulcrumed lever, a movably mounted rack carrying a metal piece, a spring actuated pawl pivotally secured to the lever and adapted to engage teeth on the rack to move it in one direction, a suitably mounted pneumatic, a spring actuated pawl carried by the pneumatic and adapted to engage teeth of the rack to move it in the opposite direction, and electrically connected contact springs suitably mounted and 10 extended into the path of the metal piece on the rack.

4. In a device of the character described, the combination with a supporting-frame, 20 of a suitably supported and spring actuated lever, a movably mounted rack carrying a metal piece, a pawl carried by the lever and adapted to engage teeth on the rack to move it in one direction, a suitably mounted pneumatic, a pawl carried by the pneumatic and 25 adapted to engage teeth of the rack to move it in the opposite direction, means actuated by the pneumatic to disengage the first

named pawl from the rack when the latter is moved by the last-named pawl, and electrically connected contact springs suitably supported and extended into the path of the metal piece on the rack.

5. In a device of the character described, the combination with a supporting-frame, 35 of a suitably fulcrumed lever, a movably mounted rack carrying a metal piece, a pawl secured to the lever and adapted to engage teeth on the rack to move it in one direction, a pneumatic suitably supported and having at one of its ends an extension, 40 a pawl mounted on said extension and adapted to engage teeth of the rack to move it in the opposite direction, a link pivotally supported at one of its ends and having a 45 pin on its other end to engage the first-named pawl, a connection uniting the link and extension on the pneumatic, and electrically connected contact springs mounted on the supporting frame and extended into the path of the metal piece on the rack.

PETER WIGGEN.
